UNITED STATES PATENT OFFICE

WILLIAM H. BERSSENBRUGGE, OF MILWAUKEE, WISCONSIN

FOLDING TABLE

Application filed May 22, 1931. Serial No. 539,259.

This invention pertains to improvements in folding tables, and more particularly to the fixtures or hardware for collapsibly attaching the legs to the table.

5 The invention has primarily for its object to provide an exceedingly simple, inexpensive, and durable fixture of the foregoing character for secure attachment of the leg, and which will effectively brace the leg when 10 extended, and provide for compact, perimetrical collapsing of the legs, as well as reinforcing the table top structure.

Incidental to the foregoing, a more specific 15 object resides in the provision of an integral table fixture for pivotally attaching both the legs and their oblique braces to the table frame to allow collapsing of the legs in parallel, intimate relation to both the table side frames and top.

20 With the above and other objects in view, which will appear as the description proceeds, the invention resides in the novel construction, combination and arrangement of parts substantially as hereinafter described and more particularly defined by the appended claims, it being understood that such changes in the precise embodiment of the 25 herein disclosed invention may be made as come within the scope of the claims.

30 In the accompanying drawing is illustrated one complete example of the physical embodiment of the present invention constructed according to the best mode so far devised for the practical application of the principles 35 thereof.

In the drawing, Figure 1 is a fragmentary bottom plan view of a conventional card table with the present invention applied thereto; and

40 Figure 2 is a section taken on the line 2—2 of Figure 1.

45 Referring now more particularly to the accompanying drawing, the invention is applied to a common type of card table comprising a rectangular frame made up of abutted side rails designated by the numeral 1, and having secured thereon in any suitable manner, a top 2. The abutting ends of the side rails may be bevelled off, as illustrated, or left square, as indicated in dotted lines, such

structure in no way affecting the present invention. Here it is also to be understood that the invention as hereinafter described is equally applicable to other structures of tables embodying side rails for supporting a 55 table top.

The present invention, which is designed for pivotally connecting the legs to the table as well as the oblique braces, comprises a 60 bracket 3, preferably formed out of a strip or blank of material, and having its greater portion secured to the inner face of one of the side rails by means of the rivets 4.

The inner end of the bracket terminates in a lateral arm 5 to which the oblique leg brace 6 is pivotally connected. Adjacent the other end of the bracket the same is provided with a lateral offset 7 having an angular extension 8 terminating in an offset foot 9 engaging the inner face of the side rail 1, the foot 9 being rigidly secured to the side rail 1 by means of a rivet 10, and the tongue projections 11 inserted into the side rail. Thus it will be seen that the lateral offset 7 to which a leg 12 is pivotally connected provides for spacing the leg 12 from the side rail 1 to enable the same to clear the arm 5 of the adjacent bracket when folded.

Cooperating with the lateral offset 7 to carry the pivotal rivet 13, on which the leg 12 is mounted, is an angle brace 14 secured to the bracket by one of the attaching rivets 4, thus providing an inexpensive, and at the same time, rigid mounting for the table leg. The outer end of the oblique brace 6 is secured to the leg 12 by a rivet 15, or other suitable means, at a point sufficiently spaced from the pivotal connection of the leg to insure rigid bracing of the same when projected. No means has been shown for latching the leg 90 against collapsing when projected, but it will be readily understood that any conventional form of sliding or hinged latch may be employed without affecting the present invention.

95 As illustrated in the drawing, wherein the legs 12 are shown in folded position, it will be noted that the oblique brace 6, which is preferably formed of relatively thin strap material, lays in intimate relation to the table 100

top to permit the adjacent leg to lay over the same, and inasmuch as the legs when folded are spaced from the inner face of the side rails, naturally the same clear the pivotal connection between the adjacent bracket arm 5.

It will also be noted that while the pivotal connection of the leg and oblique brace with the bracket 3 are remotely spaced, thus providing the desired rigidity, the integral construction of the bracket 3 results in an exceedingly strong, durable connection to avoid wobbling of the legs, and materially increase the life of the table.

Furthermore, it will be appreciated that the integral bracket, being connected to a pair of adjacent side rails, serves to materially reinforce the top supporting frame, eliminating the necessity of heavy corner fixtures.

I claim:

1. In a folding table, a table top, a pair of connected side rails secured to the table top and extending at right angles to one another, a swinging leg, a brace including a flat body portion arranged in abutting parallel relation to the inner face of one rail, a right angularly extending ear formed on the outer end of the body portion, a similar right angularly extending ear formed on the inner end of the body portion arranged in spaced parallel relation to the other rail, an angularly disposed extension formed on the last mentioned ear projecting toward the last mentioned rail, an attaching ear formed on the extension arranged in abutting parallel relation to the last mentioned rail and secured thereto, all of said ears being arranged in spaced parallel relation, an angle bracket including a pair of right angularly disposed arms one of which is disposed in spaced parallel relation to the ear on the inner end of the body portion and the other of which is arranged in abutting facial relation to the body portion, an attaching element extending through one of the rails, the body portion of the brace and the angle bracket, means pivotally connecting the leg to the angle bracket and the ear formed on the inner end of the body portion, and a diagonal brace pivotally connected to the leg and to the ear on the outer end of the body portion.

2. In a folding table, a table top, a pair of connected side rails secured to the table top and extending at right angles to one another, an attaching brace secured to the rails having an offset portion intermediate its ends and a pivot ear at its outer end, a swinging leg pivotally connected to the offset portion, and a diagonal brace having a pair of parallel ears formed on the opposite ends thereof and extending from the same side of the brace, means pivotally securing one of the ears of the diagonal brace to the leg, and means pivotally securing the other ear of the diagonal brace to the pivot ear on the outer end of the attaching brace.

In testimony that I claim the foregoing I have hereunto set my hand at Milwaukee, in the county of Milwaukee and State of Wisconsin.
